ARISTOMENES D. ADAMOPOULOS, OF SPRINGFIELD, MASSACHUSETTS.

TALKING-PICTURE MACHINE.

1,031,315.

Specification of Letters Patent.

Patented July 2, 1912.

Application filed January 2, 1912. Serial No. 668,943.

To all whom it may concern:

Be it known that I, ARISTOMENES D. ADAMOPOULOS, a Greek subject, and resident of Springfield, in the county of Hampden and State of Massachusetts, have invented certain new and useful Improvements in Talking-Picture Machines, of which the following is a full, clear, and exact description.

19 This invention relates to improvements in manually operated moving picture machines placed, as is customary, in an elevated position at the rear of an auditorium, and means for concurrently automatically and mechanically controlling a sound reproducing or talking machine at the rear of the customary white curtain which is placed in view of the audience.

The invention has for one of its objects 20 the provision of certain adjusting or synchronizing mechanisms to render it possible for the operator of the machine to adjust at will the speech or sound to be reproduced by the talking machine to bring the same in proper relation to the pictures which are 25 projected upon the screen, thereby simultaneously reproducing the speech song or verse to make what might be termed a "talking picture."

Another object is to provide means for 30 slowly or rapidly advancing the transmitter portion of the phonographic machine at such times as in the running of the film in the moving picture machine there is brought, 35 for projection on the screen, a part which has been pieced together, as necessary by reason of the film having been previously become broken or destroyed by fire, which is quite a common occurrence in machines of 40 this type.

Another object is to provide means whereby 45 the operator is enabled to determine the location in the running film of the piecing together as caused by the absence or removal of some original part of the film and the extent or length of such removed part whereby through the mechanism above referred to he may be enabled to advance the phonographic machine a little, or much, as occasion may 50 require.

Another object is to provide means to be 55 operated from adjacent the picture machine for causing temporarily a movement of the reproducer of the phonographic machine from its engagement with the record as de-

sirable at such times as the reproducer is to be advanced relatively to the record.

Other objects are to generally improve and render complete and practicable the apparatus in various departments thereof.

The invention is described in conjunction with the accompanying drawings and is set forth in the claims.

In the drawings:—Figure 1 is an elevation of a moving picture machine of ordinary or approved kind and a representation at the end of the talking machine together with the connections between the two machines. Fig. 2 is an enlarged vertical sectional view showing the details of construction to be hereinafter referred to. Fig. 3 is a front elevation of a device for operating, and indicating the extent of operating the reproducer of the phonograph as regards its advancement relatively to the cylinder or record. Fig. 3^a is a sectional view taken horizontally through the appliance shown in Fig. 3, on line 3^a, 3^a. Fig. 4 is a sectional view to illustrate means whereby when desired the phonographic machine may be operated from adjacent the picture machine without operating the latter. Fig. 5 is a plan view of the phonographic machine, certain overhead connections being understood as in horizontal section. Fig. 6 is a front elevation of the phonographic machine and novel parts combined therewith. Fig. 7 comprises a side elevation and a plan view of the mechanism provided for indicating the location of a removed part of the film and the extent of such part. Fig. 8 is an enlarged cross sectional view in detail taken on line 8—8, Fig. 5. Fig. 9 is a cross sectional view in detail taken on line 9—9, Fig. 4. Fig. 10 is an elevation, on a larger scale, of the mechanism shown at the end of the phonographic machine, being a partial repetition of the corresponding mechanism included in Fig. 1 for clearer illustration. Fig. 11 is a central vertical section longitudinally of the phonographic machine as taken on line 11—11, Fig. 10. Fig. 12 is a partial end elevation and projected partial plan to indicate the manner in which the cylindrical record may without obstruction be removed from or replaced on the rotatable support comprised in the phonographic machine therefor. Fig. 13 is a plan view on a considerably further enlarged scale to illustrate details of construction comprised in the

mechanism for advancing the reproducer relatively to the cylindrical record. Fig. 14 is a sectional elevation as seen on line 14—14, Fig. 13. Fig. 15 is a partial sectional view on line 15—15, Fig. 14.

In the drawings, Fig. 1, 1 represents the bed or table of a moving picture machine, of which 3 is the slidable lamp, and 2 represents the lens receptacle. The spools 5 and 6 are comprised in the picture machine and 7 represents the film which is caused to travel between suitable guide rolls in the ordinary operation of the machine as driven by the hand crank *a*. The hand crank 12 through a train of gearing which comprises the spur gear wheels and pinion to which the reference numeral 9 is applied drives the gear wheel 14 on a shaft 15 (which in Fig. 4 is shown as sectionally made so that one part may be in or out of clutch with the other when it may be desired to run the phonograph by the turning of the hand crank 12 without causing the running action of the film in the picture machine), and the said shaft 15 has a plurality of different radially extended cranks 16,—here four being employed of the wrist pin type which are set at quarters. These cranks are severally connected to devices or means for the driving for its talking action of the phonographic machine B.

A partial description of the phonographic machine will be here given before describing the driving connection therefor.

20 represents a horizontal stationary supporting tube mounted in standards 22 and having a longitudinal slot 23 therein.

24 represents a hollow cylinder having end heads and herein termed the "drum" 40 for supporting the record shell 25.

C represents a runner frame which is revoluble about the supporting tube 20, and on which the record drum is mounted to be revolved as one with the runner frame and 45 also to have its slow feed movement longitudinally of the runner frame. The runner frame comprises end disks 27, 27, fitted to freely turn on the tube 20 and the parallel longitudinally running and disk connecting 50 rods 28, 28. The one end disk 27 has an affixed pinion 29 through which the frame C and record drum are revolved.

30 represents the feed screw which is extended axially through the stationary tube 55 20 and is rotated independently of the revoluble runner frame C. The screw shaft 30 is engaged by the pinch nut 32 made in the shape of a tongs as indicated in Fig. 8, the jaws 33 thereof being threaded for engagement with the feed screw. The handle members 34, 34, protrude through the aforementioned slot 23 in the support tube 20 and the spring 35 holds the pinch nut closed. Such nut 32 is made as an appurtenance of 75 a runner block 36 which with such nut is

slidable along the slotway 23, without revolving, and by the engagement of the end wall of the drum 24 in the groove 37 in the runner block 36. The rotating feed screw causes the slow progressive movement of the 70 drum and record which have, of course, additional thereto rotating means therefor.

On the end of the feed screw 30 outwardly beyond one of the standards 22 is a spur gear wheel 40 in mesh with which 75 is a pinion 42 which latter is in turn meshed by a spur gear wheel 43 on the horizontal shaft 44. This shaft 44 has four wrist pin cranks 45 set at quarters thereon in exact correspondence to the wrist cranks 16 on the 80 aforementioned shaft 15 provided as before described in conjunction with the picture machine.

Directly above the shaft 15 and its wrist crank 14, near the ceiling, is a shaft or journaled member 150 having four wrist cranks 16^a of exact correspondence as to number, dimension and arrangement with the cranks 16 and a duplication of this form of crank is provided directly above the cranks 45 90 adjacent the gearing at the end of the talking machine.—the four arms of these last mentioned overhead cranks being represented by the reference character 45^b. Wires or equivalent connections 48, four in 95 number, connect the wrist pins or crank members of the cranks 16 with those 16^a; the four cranks 16^a are connected with the four cranks 45^a by the horizontally extending four wires 49; and the arms of the overhead cranks 45^a are connected with the ones 45 by the four vertical wires 50 so that the 100 rotary motion imparted to the shaft 15 at the picture machine will be imparted to the shaft 44 at the phonographic machine to 105

secure the rotation of the feed screw 30 for the longitudinal progression of the record; and the rotation of the shaft 44 is effective for securing the revoluble movement of the runner frame so that the record drum has its 110 turning movement as well as its axial motion. The shaft 44 being in train with and driving the feed screw gear 40 insures the revoluble movement of the runner frame C through means of the pinion 52 which is in 115 mesh with gear wheel 53, on a short countershaft 54 which carries a comparatively large gear 55 that is in mesh with the pinion 29 which was before described as being affixed on the end of the runner frame.

b represents the reproducer of the phonograph, 58 representing its engaging point; and *d* represents the holder for the reproducer which is shown as formed as one arm of an angular lever of which 59 is its other arm and which angular part is made tubular or with a circular eye 62 at its elbow. The eye formed elbow portion of the angular device *d*, 59, is mounted for both oscillatory and bodily sliding movement on a sup- 120 125 130

porting rod 64 which is mounted on the uprights 65 in front of the record drum. A neck portion of the tubular elbow 62 is encircled by a collar 67 which is held in place by the stop band 68 which prevents any end-wise movement or shifting of the collar relatively to the angular device. The reproducer, thus seen to be longitudinally slidable relatively to the record, may be slid as occasion therefor becomes desirable in the carrying on of a talking picture entertainment by the operator positioned at the picture projecting machine through the thrust of the upright rod 70 which has connection with a bell crank 73, which bell crank by the horizontal wires 74 connect with another overhead bell crank 75 to an arm or element of which the vertical rod 76 has connection; and upon the lower end of this rod 76 is formed or affixed a rack bar 77 which is in mesh with a comparatively long pinion 78 with which is also in mesh the rack teeth 80 of a rod or bar 79. As means for causing this comparatively slight swinging movement of the reproducer holder so that when the reproducer is to be slid longitudinally of the phonographic record without having its point in contact against the record, I provide a horizontal oscillatory rod or rock-shaft 82, one end of which is adjacent the arm 59 formed as a part of and angular to the reproducer holder *d*.—said rockshaft 82 having a short lever arm 83 carrying a rigid suitably long stud 84 ranging parallel with the line of longitudinal sliding movement which the reproducer is to have. The stud carrying arm 83 is held against a stop pin 85 by the retracting spring 86.

The rockshaft 82 has a crank arm 87, horizontally extended therefrom to which is connected a vertical wire or rod 89, the upper end of which is connected to one arm of an elbow lever 90, to the other arm of which the wire or cord connection 92 is secured, such connection 92 running to bell crank 93 to which pendent wire or cord 94 is secured, the chain having a pull handle 95 in proximity to the picture machine.

The connection.—rod 70.—has at its suitably low lower portion in proximity to the picture machine, a block or bracket 98 affixed thereon provided with an angularly extended screw threaded stud 99 which protrudes through a slot 100 in a standard 102 and extends as an upright above the bed or table of the picture machine. This screw stud extends below a gage bracket 103. A knurled thumb nut 105 screw engaging on the extremity of the stud 99 will, when tightened up, exert a clamping action to bind and hold the rod in any given set position. Another bracket 107 extends laterally of an upper portion of the standard 102, and has a vertical aperture therein through which the vertical screw shaft 108 has a bearing for free

rotative movements to the collars 109 secured on the screw shaft above and below the bracket 107 preventing relative axial movement of the screw shaft which, however, is entirely free for rotation in its bearing through the bracket. By turning the screw shaft through the means of its knurled head 110 a minute vertical adjustment may be secured to the bracket or gage 103, and in an extent to permit of adjusting movement as indicated by the scale 112 on the face of the standard 102, so that the longitudinal advancement or shifting of the reproducer relatively to the phonographic record may be accomplished to a nicety. In Fig. 3 the gage bracket 103 is considerably above the stud 99. By loosening the nut 105 and forcing it up to the gage 103, rod 70 will be moved to the extent for which provision has been made.

Connection 70 as represented especially in Figs. 1 and 2 is made in the sections 70^a and 70^b, one having screw threads 70^c and the other being tubular for a part of its length and having a telescopic relation to the screw threaded section. The tubular section is made with a yoke 70^d within which is restrained a knurled nut 113. The threads on the rod section 70^a are of such pitch as to make, in conjunction with the yoke restrained nut, a “quick” screw action of the comparatively rapid advancement, but with less accuracy as to the extent thereof of the phonograph.

G represents a dial understood as rotatable in a horizontal plane on a fixed post or journal 115, which post supports a fixed pointer 116. This dial is encircled by a graduated scale 117 with which the pointer co-operates for indication of the progress of the feeding through the picture machine of the film. The whole, or some part of the revoluble scale 117 may be understood as corresponding to the length of the film, and by memory or marking marginally on the dial the same may be made to indicate, and serve as a warning to the operator when some portion of the film comes to conjunction with the lens for which there is some inapplicable matter for reproduction by the phonograph at such time, or in other words there may be talk or song to be reproduced by the phonographic machine which would be desirably skipped for the reason that the given portion of the film is without the pictures corresponding to the phonographic matter.

The dial G is driven from the shaft 15 with which the wrist cranks at 16 are provided at quarters. The shaft 15 drives the speed reducing spur gear train 120 on the last gear of which is the bevel pinion 122 which drives the bevel pinion 123 on the upper end of a short shaft which has on its lower end another bevel pinion 124, which

drives pinion 125, shaft 126 and bevel pinion 127, which latter is in mesh with a large bevel gear wheel 128, rotatable in a horizontal plane and which carries the dial.

5 It is quite frequently desired to run the picture machine backward for various purposes, such as rewinding the film onto the spool from which it had been unwound, or for showing a reversal of action, such, for instance, as a person falling or coming out of some inclosure where on the previous forward running he had been represented as ascending or entering the inclosure; but in such reverse running of the picture machine 10 it would be very harmful to reversely propel the phonographic machine; and, therefore, as represented in Fig. 4, the shaft 15 on which the wrist cranks 16 are carried is made in two lengths or sections 15^a and 15^b, the one 15^a being in gear connection with the driving wheel of the picture machine while the cranks 16 are carried by the section 15^b. The section 15^b is endwise movable relatively to the one 15^a for a clutching and unclutching engagement therewith, one of the sections having a squared hole in its end and the other having a tenon on its end, for instance. The shaft section 15^b has a member 120 relatively to which the shaft is 15 rotative but which member being engaged between pins or collars of the shaft section necessarily moves endwise as one therewith. The member 120 has a rod 123 parallel with the axis of the shaft and it carries a catch 20 lever 124 pivoted to a suitable part or equipment thereof and which engages in a notch 125 in the stationary tubular support 127 by which the shaft sections are inclosed. The rod is guided through suitable lugs 126 25 formed as radial extensions of the tubular support 127. By releasing the catch lever 124 and sliding the shaft section 15^b out of clutch with the one 15^a, the picture machine may be reversely run without any propulsive effect on the phonographic machine; and, furthermore, it becomes possible, as in some cases may be desired, to run the phonographic machine as a continuation of the act 30 after the film may have been entirely run off,—and this, as manifest, may be done by manually rotating the set of cranks 16, when the shaft section 15^b is out of clutch as may be done by means of the crank handle fixed on the extremity of the outer or rear one of 35 the cranks indicated by the numeral 12.

The support for the outer or far end of the tube 20 on which the record drum is mounted is made in the form of a bar 130, as shown in Fig. 12 having a ring-like or yoke 40 forming middle portion 132, to receive therein for its bearing the extremity of the support tube 20. This bar is by pivot 133 connected to the top of one post or upright 22 and it is secured in its closed relation to the 45 other upright 22, oppositely related by the

spring catch 134. When the yoke bar 130 is swung open it forms no impediment to the drawing off of one record shell from the drum and the placing of another record onto the drum.

70

The crank handle 12, available for running the phonographic machine, even when the picture projecting machine may not be run, may also be utilized,—when both the projecting and phonographic machines are concurrently running,—as a helper to the picture machine operator; and the pawl 135 engaging the ratchet wheel 136 is serviceable to drive the phonographic machine backward, even although it may be made to turn the 80 picture machine in a backward direction.

75

I claim:—

1. In an apparatus of the character described, a picture projecting machine, and a phonographic machine having a revoluble record and a reproducer between which and the record there is relatively a progressive movement, and a support on which the reproducer is slidably mounted whereby its relation to the record may be changed, 85 means for operatively driving the picture machine, driving connections, operated by the operating means for the picture machine and for securing the revoluble and progressive movements of the phonographic machine, and a medium of connection, a portion of which is coöperative with, and to slidably operate, the reproducer, while another portion thereof is located, and accessible to be operated, adjacent the picture 90 machine.

95

2. In an apparatus of the character described, a picture projecting machine, and a phonographic machine having a revoluble record and a reproducer between which and the record there is relatively a progressive movement, and means for slidably supporting the reproducer whereby its normal position in relation to the length of the record may be changed, and means whereby the reproducer may have a swinging movement to and away from the record, means for operating the picture machine and means operated by the picture machine operating means for securing the revoluble and progressive 105 movements of the phonographic machine, a medium of connection, a portion of which is coöperative with, and to slidably operate, the reproducer, while another portion thereof is located and accessible to be operated 110 adjacent the picture machine, and means, having a portion thereof adjacent the picture machine, and coacting with the oscillatory reproducer for swinging the latter relatively to the record.

105

3. In an apparatus of the character described, a picture projecting machine, a phonographic machine having a revoluble record and a reproducer between which and the record there is relatively a progressive 115

120

125

130

movement, and a support on which the reproducer is slidably mounted whereby its relation to the record may be changed, means for operating the picture machine, driving connections, operated by the picture machine operating means for securing the revolute and progressive movements of the phonographic machine, a medium of connection, a portion of which is coöperative with, and to slidably operate, the reproducer, while another portion thereof is located, and accessible to be operated, adjacent the picture machine, means for moving said medium of connection, and means for gaging the extent of operation of said medium of connection.

4. In an apparatus of the character described, a picture projecting machine, having a film feeding mechanism, a phonographic machine having a revolute record and a reproducer between which and the record there is relatively a progressive movement, and a support on which the reproducer is slidably mounted whereby its relation to the record may be changed, means for operating the picture machine, driving connections, operated by the picture machine operating means for securing the revolute and progressive movements of the phonographic machine, a medium of connection, a portion of which is coöperative with, and to slidably operate, the reproducer, while another portion thereof is located, and accessible to be operated, adjacent the picture machine, and an indicator driven by, and operative in conjunction with the picture projecting machine for showing the extent of progression of the film.

5. In an apparatus of the character described, a picture projecting machine, and a phonographic machine having a revolute record and a reproducer between which and the record there is relatively a progressive movement, and a support on which the reproducer is slidably mounted whereby its relation to the record may be changed, means for operating the picture machine, driving connections, operated by the picture machine operating means for securing the revolute and progressive movements of the phonographic machine, a medium of connection, a portion of which is coöperative with, and to slidably operate, the reproducer, while another portion thereof is located in a position accessible for operation adjacent the picture machine, and provided with a screw stud, a fixed slotted and graduated scale-bar, through the slot of which the screw stud extends, and a thumb nut screwing on the stud and engageable against the scale bar.

6. In an apparatus of the character described, a picture projecting machine, and a phonographic machine having a revolute record and a reproducer between which

and the record there is relatively a progressive movement, and a support on which the reproducer is slidably mounted whereby its relation to the record may be changed, means for operating the picture machine, driving connections, operated by the picture machine operating means for securing the revolute and progressive movements of the phonographic machine, a medium of connection, a portion of which is coöperative with, and to slidably operate, the reproducer, while another portion thereof is located in a position accessible for operation adjacent the picture machine, and provided with a screw stud, a fixed slotted and graduated scale-bar, through the slot of which the screw stud extends, a thumb nut screwing on the stud and engageable against the scale bar, a gage stop adjustably movable relatively to the scale bar, and with which the said stud coacts, and means for adjusting, and confining in its adjustment, the said gage.

7. In an apparatus of the character described, a picture projecting machine, and a phonographic machine having a revolute record and a reproducer between which and the record there is relatively a progressive movement, and a support on which the reproducer is slidably mounted whereby its relation to the record may be changed, means for operating the picture machine, driving connections, operated by the picture machine operating means for securing the revolute and progressive movements of the phonographic machine, a medium of connection, a portion of which is coöperative with, and to slidably operate, the reproducer, while another portion thereof comprises a rod having a location accessible to be operated, adjacent the picture machine, said rod comprising sections which are relatively distensible and compressible and manually operated means for affecting changed longitudinal relations of said sections and for the confinement thereof.

8. In an apparatus of the character described, a picture projecting machine, and a phonographic machine having a revolute record and a reproducer between which and the record there is relatively a progressive movement, and a support on which the reproducer is slidably mounted whereby its relation to the record may be changed, means for operating the picture machine, driving connections, operated by the picture machine operating means for securing the revolute and progressive movements of the phonographic machine, a medium of connection, a portion of which is coöperative with, and to slidably operate, the reproducer, while another portion thereof comprises a vertical rod having a location accessible to be operated, adjacent the picture machine, said rod comprising sections one of which is

screw threaded and the other tubular, having a telescopic relation to the threaded section and provided with a yoke, a nut engaged by said yoke and screw engaging the 5 threaded rod section, and means for detachably confining the lower end portion of said sectionally formed rod.

9. In an apparatus of the character described, a picture projecting machine and a 10 phonographic machine having a revolute record supporting drum, a support on which the drum is endwise movable, which support is itself revolute, a feed screw shaft, engaging, and for imparting an endwise 15 progressive movement to the drum, a reproducer and a support on which the reproducer is slidably lengthwise relatively to the record drum, a shaft located adjacent the phonographic machine, means for operating 20 the picture machine, driving connections, operated by the picture machine operating means for securing the rotation of said shaft, and gearing forming driving connections between said shaft and both the said 25 feed screw and said revolute drum support.

10. In an apparatus of the character described, a picture projecting machine and operating means therefor and a phonographic machine having a revolute record 30 supporting drum, a support on which the drum is endwise movable, which support is itself revolute, a feed screw shaft, engaging, and for imparting an endwise progressive movement to the drum, a reproducer 35 and a support on which the reproducer is slidably lengthwise relatively to the record drum, a shaft located adjacent the phonographic machine, driving connections, operated by the picture machine operating 40 means for securing the rotation of said shaft, gearing forming driving connections between said shaft and both the said feed screw and said revolute drum support, and a medium of connection, a portion of which 45 is co-operative with, and to slidably operate, the reproducer, while another portion thereof is located, and accessible to be operated, adjacent the picture machine.

11. In an apparatus of the character described, a picture projecting machine and operating means therefor and a phonographic machine having a revolute record supporting drum, a support on which the drum is endwise movable, which support is itself revolute, a feed screw shaft, engaging, and for imparting an endwise progressive movement to the drum, a reproducer and a support on which the reproducer is slidably 55 lengthwise relatively to the record drum, a shaft located adjacent the phonographic machine, driving connections, operated by the picture machine operating means for securing the rotation of said shaft, gearing forming driving connections between said 60 shaft and both the said feed screw and said

revolute drum support, a rod having rack teeth, and also having a connection with the slidable reproducer, a pinion with which said teeth engage, another rack bar engaging said pinion, and a medium of connection, a portion of which is co-operative with, and to slidably operate, the second named rack bar, while another portion thereof is located, and accessible to be operated, adjacent the picture machine. 70

12. In an apparatus of the character described, a picture projecting machine and operating means therefor and a phonographic machine having a revolute record supporting drum, a support on which the 80 drum is endwise movable, which support is itself revolute, a feed screw shaft, engaging, and for imparting an endwise progressive movement to the drum, a reproducer and a support on which the reproducer is 85 both slidably lengthwise relatively to the record drum, and adapted for a rocking movement, a shaft located adjacent the phonographic machine, driving connections, operated by the picture machine operating 90 means for securing the rotation of said shaft, gearing forming driving connections between said shaft and both the said feed screw and said revolute drum support, a rod having rack teeth, and also having a connection 95 with the slidable reproducer, a pinion with which said teeth engage, another rack bar engaging said pinion, a medium of connection, a portion of which is co-operative with, and to slidably operate, the second named 100 rack bar, while another portion thereof is located, and accessible to be operated, adjacent the picture machine, and means extending from adjacent the picture machine to connection with, and for rocking the reproducer. 105

13. In an apparatus of the character described, a picture projecting machine and operating means therefor, and a phonographic machine having a revolute record 110 and a reproducer between which and the record there is relatively a progressive movement, and means for slidably supporting the reproducer whereby its normal position in relation to the length of the record may be 115 changed, and means whereby the reproducer may have a swinging movement to, and away from the record, driving connections, operated by the picture machine operating 120 means for securing the revolute and progressive movements of the phonographic machine, a medium of connection, a portion of which is co-operative with, and to slidably operate, the reproducer, while another portion thereof is located and accessible to be 125 operated adjacent the picture machine, a rock shaft having an arm for engaging the reproducer, and means, having a portion thereof adjacent the picture machine and co-acting with the said rock shaft for securing 130

the swinging movement of the reproducer relatively to the record.

14. In an apparatus of the character described, a picture projecting machine having a revolute propulsion member with which is associated a set of variably radial cranks and a phonographic machine with the revolute propulsion member of which is associated a similar set of variably radial cranks, 15 like sets of cranks above those of the picture and phonographic machines and wires forming connections between the cranks of

the picture machine thereabove, and between the latter cranks and those above the phonographic machine and between the last mentioned cranks and those appurtenant to the phonographic machine.

Signed by me at Springfield, Mass., in presence of two subscribing witnesses.
